Filed Apr. 27, 1961, Ser. No. 106,001

11 Claims. (Cl. 214—302)

This invention relates to improvements in containers of the character adapted for use in collecting and transporting materials.

One satisfactory way of handling loose material is to provide containers of suitable size into which the material can be deposited. In the collection of refuse, for example, several containers may be placed at convenient locations and emptied from time to time as they are filled. Such containers may be provided with a drop bottom door which opens for dumping the contents from the container. Normally the container is filled while sitting on the ground or other supporting surface, and the material is placed in the container through doors provided for this purpose in the upper portion of the container.

After the container is full it may be lifted onto a vehicle by means of a hoisting apparatus on the vehicle, and then transported to a point where the contents of the container are dumped. The empty container is then returned to the same location or to a new location for refilling.

The drop bottom door provided on such containers is hinged to the body of the container so that it may swing downwardly therefrom. When the container is resting upon the ground, the drop bottom door is closed and fits snugly with the bottom portion of the container to provide a closure therefor.

Hoisting apparatus for handling this type of drop bottom container is disclosed in prior patents; for example, Patent No. 2,281,183, issued April 28, 1942, and Patent No. 2,369,722, issued February 20, 1945.

In the operation of this type of hoisting apparatus for lifting a drop bottom container onto a vehicle, the container is picked up in a manner whereby the drop bottom door is held closed during the transporting of the container to the dumping location. When it is desired to dump the contents from the container, the body of the container is held in an elevated position and the drop bottom door is allowed to swing downwardly thereby opening the bottom portion of the body so that the material is free to flow from the container.

Such hoisting apparatus used for handling drop bottom containers inherently provides that the drop bottom door will be held firmly closed when the container is lifted onto or lowered from the transporting vehicle. When such containers are resting upon the ground or other supporting surface, the body portion of the container fits snugly over the drop bottom door and the weight of the body portion prevents an inadvertent opening of the bottom portion of the container.

Other types of equipment used in handling containers which hold loose material, such as trash for example, are referred to generally as front end loaders or front end loading equipment. These types of hoisting equipment usually employ a pair of lifting arms which are pivotally connected to the transporting vehicle and extend to the front of the vehicle where a connection is established between the lifting arms and the container. One such type of front end loading equipment is shown, for example, in Patent No. 2,900,096, issued August 18, 1959, wherein the front end loading equipment includes, in addition to the pair of lifting arms, a front torque tube extending across the vehicle and connecting the lifting arms, and a pair of fork arms mounted on the torque tube and serv-

2

ing to establish a detachable connection between the container and the lifting arms.

In this type of front end loading equipment the fork arms extend along the outside of the container and fit into pockets at the ends of the container provided for receiving the fork arms. Actuation of the lifting arms and the fork arms by suitable power means is effected in order to lift the container over the cab of the vehicle to a position above the body of the vehicle so that the contents of the container may be dumped through a hopper into the body. The empty container may thereafter be swung back to a position on the ground in front of the vehicle.

When containers are emptied by such front end loading equipment, it is not necessary to transport the containers themselves to a distant location for dumping. A vehicle equipped with this type of front end loading equipment and with a suitable body is driven from point to point where various containers are located. One after another the full containers may be emptied into the body of the vehicle, and once the body is full, then the vehicle can make a trip to the dumping area and the contents emptied from the body. In this manner, it is not necessary to remove the containers from the filling location, and the number of trips which the vehicle must make to the dumping location can be minimized.

The containers used in connection with front end loading equipment generally include a bottom which is integral with or permanently connected to the body portion of the container. Suitable types of openings are provided at or near the top portion of the body of the container through which material may be placed in the container.

In the use of containers of the type which are employed with front end loading equipment it is not necessary that the bottom of the containers be provided with a drop bottom door. In fact, it is absolutely essential that during the dumping operation of these containers, the bottom portion of the containers remain fixed or closed. When the lifting arms of the front end loading equipment swing a container upwardly, the material within the container rests on the bottom of the container. Therefore, it is essential that a suitably strong bottom be provided for such containers.

The two types of containers described, that is, containers with a drop bottom door, and containers with a fixed bottom, have in the past been useable only with the two different types of hoisting apparatus which have been described. In addition to having the different types of construction at the bottom portion of the containers, these two types of containers have been provided with different types of means whereby they could be accommodated by either type of hoisting apparatus.

It is important to note in this connection that the two types of containers previously described, and the two types of hoisting apparatus, have become very successful in the past. Consequently, there are in existence a large number of both types of containers and a large number of both types of equipment used for hoisting these containers. Consequently, it is necessary, when considering the problem of providing a container which can be accommodated by both types of hoisting apparatus, that the hoisting apparatus itself not be modified because it is necessary that such hoisting apparatus still be available for use in connection with the two different types of containers.

Accordingly, it is the primary object of this invention to provide a device for use in connection with drop bottom containers whereby such containers may be used with front end loading equipment as well as other types of hoisting apparatus.

This may be accomplished by providing a sleeve assembly on each opposed end wall of the drop bottom

container. Each assembly includes a sliding sleeve member which can be adjusted to a rearward position so that hoisting apparatus may be employed in connection with the drop bottom door, or to a forward position so that front end loading equipment may be employed to handle the container. A plate member is connected to and movable with the sliding sleeve member, and has a notch at its forward end for receiving therein a pin on the drop bottom door. When the sleeve member is moved to its forward position the pin and plate cooperate to hold closed the drop bottom door.

This embodiment of the invention is illustrated in the accompanying drawings, in which:

FIG. 1 is a side elevation view of a vehicle equipped with hoisting apparatus for use with containers which have a drop bottom door, and shows in full lines and broken lines a container embodying certain aspects of this invention;

FIG. 2 is a side elevation view of a vehicle equipped with front end loading equipment, and shows in connection therewith the container illustrated in FIG. 1;

FIG. 3 is an enlarged side elevation view of a sliding sleeve assembly;

FIG. 4 is an end elevation view corresponding with FIG. 3, wherein a portion of the container is shown in cross section; and

FIG. 5 is a sectional view taken along line 5-5 of FIG. 3.

In FIGS. 1 and 2 there is illustrated a container 10 of the type having a drop bottom door 12 hinged, or otherwise pivotally connected at 14 to the body of the container. This type of drop bottom container 10 is adapted for use with any form of hoisting apparatus suitable for accommodating such drop bottom containers. This hoisting apparatus might include either a truck mounted hoisting unit, as shown in Patent No. 2,281,183, issued April 28, 1942; a self-propelled vehicle, as shown in Patent No. 2,751,100, issued June 19, 1956; a hoisting unit of the character shown in Patent No. Re. 23,546, issued September 9, 1952; or a fork lift type of hoisting unit. In FIG. 1, the container 10 is illustrated in connection with one form of hoisting unit, but it will be understood that the container 10 may be used with any other form of hoisting apparatus capable of handling drop bottom type containers.

The form of hoisting apparatus 19 shown in FIG. 1 is mounted on a self-propelled vehicle 15 having a chassis indicated generally by the numeral 16. A subframe assembly 18 is mounted on the chassis 16 and includes a bucket rest 20 for supporting the container 10, which as illustrated in FIG. 1, is located at the rear end of the chassis 16. The container 10 is adapted to be pulled upon and held against a carriage assembly 22 which is capable of movement forwardly and backwardly relative to the chassis 16, as described in detail in Patent No. 2,281,183. A pair of booms 23 are located above the chassis 16 and have swinging movement in a vertical direction.

The drop bottom door 12 of the container 10 is hinged at 14 to a front wall 24 at the bottom of the body portion of the container. The container 10 is provided with a rear wall 25 and opposed end walls 26 having notches 28 therein at the bottom for receiving upwardly extending triangular-shaped end plate 30 of the drop bottom door 12. These end plates 30 are shaped to fit within the notches 28 when the drop bottom door 12 is closed.

The end plates 30 have fixed thereto lifting pins or lugs 32 which protrude outwardly from the end plates 30 for connection by a chain 34 or other type of flexible member of the hoisting apparatus 19. The chains 34 are connected to the upwardly extending ends of the booms 23. When the free ends of the chains 34 are connected with the lifting pins 32, and when the booms 23 are swung upwardly, the container 10 is hoisted from

the ground onto the lifting mechanism 19. A toe member 35 is fixed on the free end of the pins 32 to hold the chain 34 thereon.

The opening and dumping operation of the container 10 is accomplished by holding the body portion of the container 10 suspended on the carriage assembly 22 by means of a hook on the carriage assembly 22, which hook engages a bail on the front wall 24 of the container 10. The hook and the bail are illustrated and described in detail in Patent No. 2,729,496, issued January 3, 1956. When the body portion of the container 10 is held suspended on the carriage assembly 22, the booms 23 may be lowered, thereby allowing the drop bottom door 12 to swing downwardly, as illustrated in broken lines in FIG. 1.

The servicing of a full container 10 by a vehicle 15 equipped with the hoisting apparatus 19 is carried out as follows. The vehicle 15 is backed up to the container 10 as the container rests upon the ground or other supporting surface. The chains 34 are connected with the lifting pins 32 on the end plates 30, and the hoisting apparatus 19 is actuated to lift the container 10 onto the vehicle chassis 16. The container 10 is then transported to a dumping location where the hoisting apparatus 19 is actuated to open the drop bottom door 12 in order to allow the contents of the container 10 to fall out.

The hoisting apparatus 19 is then actuated to close the drop bottom door 12, and the empty container 10 may be returned to the same location or transported to a new location for refilling. Then the container 10 is lowered onto the ground and the chains 34 disconnected so that the vehicle 15 may be employed to service other containers in a similar manner.

In FIG. 2 there is illustrated one type of front end loading equipment which may be employed to empty the contents of the container 10. It is customary to use a vehicle of the character generally indicated by the reference numeral 40 which is self-propelled under the control of an operator located within a cab 42.

A body 44 is provided on the vehicle chassis behind the cab 42 and may be of any suitable type for receiving the particular material to be handled, and may be provided with packer mechanism for compressing the material, if this is desired. The top portion of the front of the body 44 is provided with a filling opening or hopper 46 through which material may be dumped into the body 44. The character of the body otherwise may be varied as desired.

The front end loading equipment or hoisting apparatus used in connection with the vehicle 40 is indicated in FIG. 2 by numeral 50 and includes a pair of lifting arms 52 spaced apart a distance corresponding substantially with the width of the cab 42. The lifting arms 52 may be of gooseneck shape or inverted U-shape, for example, so as to extend over the top and downwardly in front and back of the cab 42, as illustrated in FIG. 2.

At the back of the cab 42 the lower ends of the lifting arms 52 are fixed on a rear, horizontally extending torque tube or rod 54 which extends substantially from one side of the vehicle 40 to the other. The torque tube 54 is journaled in bearing boxes which are fixably mounted on the vehicle chassis. In this manner the lifting arms 52 are pivotally mounted to the vehicle 40. Lever arms 56 are fixed on the torque tube 54 and extend downwardly therefrom. The free ends of the lever arms 56 are pivotally connected at 58 to suitable power devices 60, such as a conventional hydraulically actuated cylinder and piston devices, which in turn are mounted on the vehicle chassis.

At the front of the vehicle 40 the lifting arms 52 are connected by a horizontally extending front torque tube or rod 62 which is journaled in bearing boxes secured to the forward ends of the lifting arms 52. On each outside end of the torque tube 62 there is fixed a pair of lever arms 64. A power device 66, such as a conven-

tional hydraulically actuated cylinder and piston device, is mounted on each of the lifting arms 52 by means of a bracket 68 so that the power device 66 extends along the corresponding arm 52. The free end of a piston rod 70 of the power device 66 is connected to the free end of the corresponding lever arm 64. A pair of fork arms 72 are rigidly mounted near opposite ends of the torque tube 62 and have attached to their free ends a tow plate 74.

On opposite end walls 26 of the container 10 there is securely attached a sleeve assembly 100. Each of the sleeve assemblies 100 receives therein one of the fork arms 72 of the lifting mechanism 50. The sleeve assemblies 100 will be described in detail below.

The hoisting apparatus 50 is operated as follows in order to dump the contents of the container 10 into the body 44. The power device 66 may be actuated under the force of hydraulic pressure in order to rotate the lever arms 64 which in turn rotates the torque tube 62 so as to properly align the fork arms 72 for entrance into the sleeve assemblies 80. The lifting arms 52 may be pivoted about the axis of the rear torque tube 54 by operation of the power devices 60. In order to establish a connection between the lifting mechanism 50 and the container 10 while it is on the ground or other supporting surface in front of the vehicle 40, the vehicle is maneuvered into the proper position and then the power devices 60 and 66 are operated so that the fork arms 72 are at the proper angle with respect to the sleeve assemblies 80 so as to effect a suitable connection between the fork arm 72 and the sleeve assemblies 80.

The power devices 60 are operated further to swing the lifting arms 52 upwardly whereby the container 10 is hoisted over the cab 42 and into dumping position at the top and front of the body 44. Simultaneously, the fork arms 72 may be actuated by the power devices 66 to rotate slightly in a counterclockwise direction, with reference to FIG. 2, so that the container 10 may be kept tilted slightly toward the vehicle but substantially upright during the swinging movement above the body 44. Once the container 10 is above the hopper 46 the fork arms 72 may be actuated to rotate in a clockwise direction far enough so that the container 10 is inverted to dump the contents thereof through the hopper 46 and to the body 44.

After the contents of the container 10 are dumped in this manner, the power devices 66 may be actuated to rotate the fork arms 72 so that the container 10 will be returned to a generally upright position. The lifting arms 52 then may be lowered by proper actuation of the power devices 60 to lower the container 10 to the ground in front of the vehicle 40.

As pointed out previously, the containers employed with the hoisting apparatus 19, illustrated in FIG. 1, are provided with drop bottom doors. When the body portions of such containers are suspended above the ground, these drop bottom doors are free to swing downwardly. When it is desirous to use these containers with the hoisting apparatus illustrated in FIG. 2, for example, it is necessary that the drop bottom doors of the containers be held closed, but it is also necessary that the drop bottom doors be ready for use again with the hoisting apparatus illustrated in FIG. 1.

In FIGS. 3-5 there is illustrated the sleeve assembly 100 which has been referred to previously. One such sleeve assembly is provided on each opposite end wall 26 of the container 10, and as described previously, is adapted to receive therein a fork arm 72 of the hoisting apparatus 50.

Each sleeve assembly 100 includes a hollow sleeve member 102 which may be formed of a channel member and a plate member, for example, as illustrated in FIGS. 4 and 5. The sleeve member 102 provides an opening extending longitudinally therethrough for unobstructed entrance of a fork arm 72. A suitable number of U-shaped braces 104 are fixed to the end wall 26 of the container 10, as by welding, and each brace may be strength-

ened by gussets 106 as necessary. The sleeve member 102 fits loosely between the U-shaped braces 106 and the end wall 26 of the container 10 and may slide lengthwise therebetween. Such lengthwise movement is limited by collars 108 provided at each end of the sleeve member 102.

In FIG. 1 the sleeve member 102 is shown in a position wherein it has been moved to its extreme position towards the rear of the container 10. In FIG. 2, the sleeve member 102 is shown in a position wherein it has been moved to its extreme position towards the front or the center of the container 10.

In order to hold the sleeve member 102 in either one of its extreme positions, a position adjuster 110 is provided. The position adjuster 110 is mounted on the end wall 26 of the container 10 by means of an angle member 112 and includes a short sleeve 113 through which extends a plunger 114. An enlarged head portion 115 of the plunger 114 extends downwardly and outwardly of the sleeve 113. Within the sleeve 113 a spring 116 bears on the enlarged head portion 115 and tends to force the head portion 115 to its outwardly extended position.

A ring 118 which is larger in diameter than the sleeve 113 is connected to the upper end of the plunger 114 and extends upwardly above the sleeve 113 so as to be in a position to be grasped. Also, the ring 118 serves to prevent the plunger 114 from sliding out of the sleeve 113 due to the action of the spring 116.

The head portion 115 of the plunger 114 is adapted to fit into either one of two holes 122 or 124 located in the top portion of the sliding sleeve member 102. The holes 122 and 124 are spaced apart a suitable distance longitudinally with respect to the sleeve member 102 so that when the sleeve member 102 is in the position illustrated in FIG. 1 the hole 124 will be aligned with the head portion 115 of the position adjuster 110, and when the sleeve member 102 is in the position illustrated in FIG. 2, the hole 122 will be aligned with the head portion 115.

The top edge of the short sleeve 113 is provided with a shallow notch 126. The ring 118 may be grasped and pulled upwardly thereby pulling the plunger 114 and the head portion 115 upwardly and out of either one of the holes 122 and 124. Then the ring 118 may be twisted approximately 45 degrees in either rotational direction and released so that the spring 116 will pull the ring 118 downwardly and into the notch 126. When this is done, the head portion 115 is above the sleeve member 102 and the sleeve may be adjusted easily to either one of its extreme positions without interference from the head portion 115. After the ring 118 is turned to the position illustrated in FIG. 3, the lower part of the ring fits into deep notches in the top edge of the sleeve 113 so that the head portion 115 may fit into either one of the holes 122 or 124.

When it is desired to use the container 10 with the hoisting apparatus 19 illustrated in FIG. 1, the sleeve member 102 of the sleeve assembly 100 can be moved to its rearward position as illustrated in FIG. 1 and held in this position by the adjuster 110. The sleeve member 102 is then out of the way of the chains 34 of the hoisting apparatus 19. The chains 34 then can be connected easily to the lifting pins 32 and they are free to move with respect to the container 10 without interference from the sleeve member 102.

On the other hand, when it is desired to use the container 10 in connection with the hoisting apparatus 50 illustrated in FIG. 2, the sleeve member 102 of the sleeve assembly 100 can be moved to its forward position as illustrated in FIG. 2 and held there by the adjuster 110. When the sleeve 102 is in its forward position it is adjacent the center of the container 10. This creates a balanced condition when the fork arms 72 of the lifting apparatus 50 are inserted in the sleeve members 102 and employed to hoist the container 10 above the vehicle 40. The fork arms 72 thereby apply their lifting force

at a point suitably close to the center of the container 10.

Extending longitudinally of the sleeve assembly 100 and parallel with the sleeve member 102 there is a rectangular shaped bar 130, the ends of which are rigidly fixed with the C-shaped end retaining members 108 on the sleeve member 102. Rigidly fixed to the bar 130 and depending downwardly therefrom beneath the sleeve member 102 there is a plate 132. The forward end of the plate is provided with a notch 134 which is slightly larger than the diameter of the pin 32 on the drop bottom door 12.

In FIG. 3 the sleeve member 102 is shown in its forward position. In this position, the plate 132 is moved to its forward position along with the sleeve member 102, and the notch 134 in the plate 132 receives the pin member 32. With the adjuster 110 having its head portion 115 extending into hole 122, the sleeve member 102 and in turn the plate 132 is locked in the position illustrated in FIG. 3, while a protruding portion 136 of the plate 132 extends beneath the pin 32.

With the sleeve assembly 100 adjusted to the position just described, the container 10 is ready for use in connection with the lifting apparatus 50 illustrated in FIG. 2. The fork arms 72 may be inserted through the sleeve members 102 to establish a connection between the lifting assembly 50 and the container 10. As the lifting arms 52 are actuated to swing upwardly, the fork arms 72 in turn move upwardly in contact with the upper portion of the sleeves 102, and because the sleeve assembly 100 is secured firmly to the side 26 of the container 10, the container in turn will be swung upwardly. As the container 10 is moved upwardly in this manner, portion 136 of the plate 132 pulls upwardly on the lifting pin 32. Consequently, the drop bottom door 112 will be moved upwardly with the body portion of the container 10 and will not be free to swing downwardly.

The sleeve assembly 100 may be used with containers of various sizes so that they may be employed with front end loading equipment as well as with hoisting apparatus used in connection with drop bottom doors. Existing drop bottom containers may be converted to use with front end loaders, yet they may still be employed as drop bottom containers. The notched plate 132 automatically latches closed the drop bottom door, and automatically unlatches the door as the sliding sleeve 102 is adjusted to the desired position.

While the invention has been illustrated and described in a certain preferred embodiment, it is recognized that other variations and changes may be made therein without departing from the invention as set forth in the claims.

We claim:

1. The combination with a container having a drop bottom door, of longitudinally extending sleeve means for establishing a connection with hoisting apparatus, said means being movable longitudinally, and means on the sleeve means and movable therewith for holding the drop bottom door closed.

2. The combination with a container having a drop bottom door, of sleeve means for establishing a connection with hoisting apparatus, said sleeve means being movable to various positions with respect to the container, means connected with the sleeve means and movable therewith for holding the drop bottom door closed; and means for holding the sleeve means in the various positions.

3. The combination of a container, a drop bottom door hinged to the container, first hoisting means engageable with the door for hoisting the container, longitudinally extending sleeve means on the container, second hoisting means engageable with the sleeve means for hoisting the container, said sleeve means being movable longitudinally, and means on the sleeve means and movable therewith for selectively holding the door closed.

4. The combination of a container having a body including front and rear walls and opposed end walls, a

door hinged to the body and serving as a bottom for the container when closed, pin members on the door, and longitudinally extending sleeve members on the end walls; said sleeve members being movable longitudinally, hoisting means engageable with the pin members on the door for hoisting the container; second hoisting means engageable with the sleeve members for hoisting the container, said hoisting means being useable alternatively; and means on the sleeve members and movable therewith for holding the door closed when the second hoisting means is used.

5. The combination of a container having a body including front and rear walls and opposed end walls, a door hinged to the body and serving as a bottom for the container when closed, pin members on the door, and longitudinally extending sleeve members on the end walls; said sleeve members being movable longitudinally, hoisting means on a vehicle and engageable with the pin members on the door for hoisting the container onto the vehicle; second hoisting means on another vehicle having a body and engageable with the sleeve members for hoisting the container above the body, said hoisting means being useable alternatively; and means on the sleeve members and movable therewith for holding the door closed when the second hoisting means is used.

6. The combination with a container having a bottom discharge door, said door having a projection thereon extending outwardly from the container, of sleeve means for establishing a connection with hoisting apparatus, said sleeve means being movable to various positions with respect to the container, means connected with the sleeve means and movable therewith for engaging said projection for holding the bottom discharge door closed.

7. The combination with a container having a bottom discharge door, said door having a projection thereon extending outwardly from the container, of a sleeve for receiving a lifting arm of hoisting apparatus, brackets, said brackets being spaced apart and each having an opening therein, said sleeve extending through said bracket openings, means for securing the brackets to the container, and means on the sleeve for engagement with said projection upon longitudinal movement of said sleeve in said brackets, whereby the door is held closed during lifting of the container by the hoisting apparatus.

8. Apparatus for establishing a connection between front end loading type hoisting apparatus and a container of the type having end walls and a bottom discharge door with upturned ends substantially coplanar with the end walls, and having projections on said door ends, comprising a sleeve for receiving a lifting implement of said hoisting apparatus, said sleeve having an elongated bearing surface therein, bracket means adapted to be secured to one of said end walls, means mounting said sleeve in said bracket means for longitudinal movement relative thereto, said bracket means overlapping said bearing surface of said sleeve, and means on the sleeve for selectively engaging said projection upon longitudinal movement of said sleeve, whereby the bottom discharge door is held closed while the container is lifted by said hoisting apparatus.

9. Apparatus for use with a container of the type having end walls and a bottom discharge door with upturned ends substantially coplanar with the end walls, and having a projection on each door end extending outwardly therefrom, said apparatus including a sleeve having an elongated bearing surface therein for engagement by a lifting arm of hoisting apparatus, brackets for securing the sleeve to one of said end walls, said brackets overlapping a portion of said sleeve and said bearing surface, said sleeve bearing surface extending through said brackets and movable longitudinally in said brackets, and a plate secured to said sleeve in position for selectively engaging said projection upon longitudinal movement of said sleeve whereby the door is held closed while the container is lifted by a hoisting apparatus engaging said sleeve.

10. Apparatus for establishing a connection between front end loading type hoisting apparatus and a container of the type having end walls and a bottom discharge door with upturned ends substantially coplanar with the end walls, and having a projection on each door end, comprising a sleeve for receiving a lifting implement of said hoisting apparatus, said sleeve having an elongated bearing surface therein, bracket means adapted to be secured to one of said end walls, means mounting said sleeve in said bracket means for longitudinal movement relative thereto, said bracket means overlapping said bearing surface of said sleeve, means on the sleeve for selectively engaging said projection upon longitudinal movement of said sleeve, and means for releasably holding the sleeve in a forward or rearward position, whereby the bottom discharge door is held closed while the container is lifted by said hoisting apparatus.

11. Apparatus for establishing a connection between front end loading type hoisting apparatus and a container of the type having end walls and a bottom discharge door with upturned ends substantially coplanar with the end walls, and having a projection on each door end, comprising an elongated tubular sleeve having a bearing sur-

5
10
15
20

face therein for receiving a lifting implement of said hoisting apparatus, bracket means adapted to be secured to one of said end walls, means mounting said sleeve in said bracket means for longitudinal movement relative thereto, said bracket means encircling said bearing surface of said tubular sleeve, and means on the sleeve for selectively engaging said projection upon longitudinal movement of said sleeve, whereby the bottom discharge door is held closed while the container is lifted by said hoisting apparatus.
